VAGINAL OBTURATOR

Filed Jan. 29, 1942

UNITED STATES PATENT OFFICE

2,391,343

VAGINAL OBTURATOR

Otto Popper, Johannesburg, Transvaal, Union of
South Africa

Application January 29, 1942, Serial No. 428,781

3 Claims. (Cl. 128—127)

This application is a continuation-in-part of my copending application bearing Serial Number 369,678, filed December 11, 1940.

In cases of perineal tears, rectovaginal fistula or vesico-vaginal fistula, it is desirable to protect the cervix and its adnexa from foreign matter originating from said sources. Generally this is done (preliminary to operation) by packing off the vagina by prolonged postural treatment, lavage, etc.

This invention relates to devices for obturating the vaginal cavity around the cervix uteri.

An object of the invention is to provide a compact and light obturator which is well adapted to be securely fixed in its proper position in the vagina and which securely shields the cervix and its adnexa but leaves free the lower portion of the vaginal tract and thus avoids discomfort to the patient.

An obturator according to this invention consists of a deformable diaphragm which, in its expanded form, is of materially disc shape and stiff against radial deformation and circumferentially collapsible upon deformation out of the general plane of the disc, and thus capable of assuming a folded position in which it is of rod form of substantially less diameter than the disc, in which rod form the radial stiffness of the expanded form is present as endwise stiffness, and the periphery of the disc is collapsed and forms one end of the rod form.

It is thus adapted to be introduced into the vagina while in its folded form and, when properly positioned therein, to be expanded to its disc form in which its periphery dilates and engages in the walls of the vagina around the cervix, and it is of proper shape to perform its obturating function.

The invention is illustrated in the accompanying drawing in which:

Figure 1 is a perspective view of a preferred construction of the obturator.

Figure 2 is an elevation thereof, sectioned across its diameter.

Figure 3 is the plan, shown on a larger scale, of the central portion of the spring element of Fig. 1.

Figure 4 is a longitudinal section of an applicator containing the obturator in its folded state.

Figure 5 is a cross section of Figure 4 on the plane 5—5.

Figures 6 and 7 show the manner of inserting the obturator.

Referring to Figs. 1, 2 and 3, the deformable diaphragm comprises a circular or elliptical disc

10 formed of two plies 11, 11 of readily flexible, and usually impervious, sheet material, such as tough rubber sheet thin enough to be of negligible stiffness. The diaphragm also comprises element 12 comprising a number of radial arms 13 consisting of diametrically complete strips of spring material which is other than rubber, and which does not acquire a permanent set when stored for months or even years in a folded condition. The preferably used material is spring steel; but bronze and other metals, as well as such synthetic resins as have the necessary elasticity, may be also used. The strips 13 are superimposed on one another and are all connected 15 together, as by a binding 14, which does not impair the elasticity and strength of the individual diametral strips. Said element 12 is positioned between the plies 11, 11 and is sealed between them by fusing or cementing said plies to one 20 another; conveniently at the circumferential zone 15. A withdrawing cord 16 is attached to the assembly, as by being passed through a small hole in the lower ply 11 and looped around the hub 17 of the arms 13.

25 The arms 13 are of such length and stiffness that when the obturator is positioned in its expanded form at the upper end of the vaginal canal, as shown in Fig. 7, said arms dilate the vaginal walls 18 around the cervix uteri 19 to an extent that ensures the firm lodgment of the obturator in the canal.

30 The stiffness of the arms is stiffness in the general plane of the diaphragm in its expanded form (Figs. 1, 2, 3 and 7) and such stiffness is provided by making the arms of proper breadth, while on the other hand being thin enough to deform in the manner necessary to fold the diaphragm. The arms are sufficient in number, preferably six or eight (formed by 3 or 4 diametrically complete strips), for their extremities 35 20 to define the angles of a polygon which is a fairly close approximation to a circle, so that in dilating the vagina, the periphery of the diaphragm will exert a materially equal pressure thereon at all circumferential points and thus make uninterrupted peripheral contact therewith.

35 The collapsed or folded form of the diaphragm is indicated by 10a in Fig. 4. In this collapsed form, the arms 13 are elastically bent up around the hub 17 and pressed together so that they become substantially parallel with one another and with the axis of the disc; the flexible material of the disc 10 being folded or elastically 40 shrunk between the arms. The materially disc-

shaped diaphragm thus assumes the form of a rod, one end 21a of which consists of the central zone 21 of the disc 10 and the other end 15a of which consists of the collapsed periphery 15 of the disc. Provision being made for restraining the arms 13 from springing back to their expanded positions, their former radial stiffness now appears as lengthwise stiffness of the rod, enabling it to sustain endwise thrust for inserting it lengthwise into the vagina. In the use of the obturator, it is passed in this folded form into position in the vagina, whereupon the restraint upon the arms is removed and the diaphragm is allowed to expand and lodge itself in position by dilating the vaginal walls as mentioned above.

Preferably it is thus restrained, introduced and released by means of an applicator comprising a tube 22 of suitable diameter and external smoothness to be passed into the vagina. The proximal end of the tube 22 forms a socket 23 within which the obturator is positioned with its end 15a as the proximal end. The diameter of tube 22 is about half an inch and the tube is long enough to extend well from the vagina when its proximal extremity 24 is close to the cervix uteri. Slidable within the tube is a plunger 25, by relative movement of which towards the proximal end of the tube, the obturator can be relatively ejected from the socket 23. The plunger is manually controlled by means of a tab 26 which extends through a slot 27 in the side of the tube towards the distal end thereof, and is spaced well away from the obturator by the length of the plunger so that it remains outside the vagina.

The procedure in introducing the obturator by means of the applicator described, is to pass the assembly of Fig. 4, with its end 24 first, into the vagina as far as it can conveniently be passed, as indicated by the dotted lines 24x, Fig. 6. This brings the obturator into a favourable position with respect to the vagina, although still confined in the tube. The tab 26 is now held steady by the fingers 28 (Fig. 6); and the tube 22 is withdrawn past the obturator while the latter is held stationary by the plunger 25.

As the tube 22 is withdrawn from the obturator, the latter elastically expands, and the whole of its expanding periphery simultaneously engages the vaginal wall. At this stage both the tube 22 and the plunger 25 are wholly withdrawn; and, if of appropriate material such as paper, they may be discarded into a flushing system.

The anterior peripheral portion 29 of the expanding obturator tends naturally to lodge in the region of the anterior fornix 30 as shown in Fig. 7. The arrival of the diametrically opposite peripheral portion 31 into the posterior fornix 32, as shown in Fig. 7, may occur automatically. One factor tending to bring it to that position is that the unexhausted tendency of the obturator rim to expand causes said portion 31 to slide along the vaginal wall into the region where the vaginal wall is less restrictive to such expansion. Another factor is the slightly vacuous condition set up in the upper end of the vagina by its lateral

expansion and the resulting unbalanced air pressure on the distal face of the diaphragm. If neither of these factors is operative, the obturator can be brought into about the Fig. 7 position by slight pressure.

It is preferred to make the diameter over the arms 13 rather less than the diameter of the disc 10 so that the peripheral zone 15 forms a flexible fringe around the radially rigid area of the disc. When the obturator is within the vagina said fringe lies along the vaginal wall and thereby assists in sealing the periphery of the obturator with the vaginal wall.

The obturator is withdrawn from the vagina by traction on the cord 16. When being thus withdrawn it can contract more or less to its folded form and thus pass easily through the smaller and more muscular orifice of the canal.

In the case of the combination comprising the obturator and the tubular applicator, the intention is that the complete article comprising the obturator folded and positioned within the applicator as shown in Fig. 1, shall be manufactured and packed for sale. Some period of time will thus occur between the manufacture and the use of the article.

The provision of the diametral spring arms made of a material which does not acquire a permanent set when stored for long periods in a folded condition, ensures that the elasticity of the obturator is preserved during the aforesaid period; which is not the case when the elasticity depends on rubber, since the latter acquires a permanent set after a short time.

35 I claim:

1. A vaginal obturator consisting of a deformable diaphragm which, in its expanded form, is of materially disc shape and stiff against radial deformation and circumcentrically collapsible upon deformation out of the general plane of the disc, and thus capable of assuming a folded position in which it is of rod form of substantially less diameter than the disc, in which rod form the radial stiffness of the expanded form is present as endwise stiffness and the periphery of the disc is collapsed and forms one end of the rod form; said obturator comprising a disc of flexible material and a spring element tending to bring the disc to its expanded form and to hold it in such expanded form; said spring element comprising a plurality of radial arms formed by diametrically complete strips of spring material; said strips being superimposed on one another and connected together by means which do not impair the elasticity and strength of the individual strips.

2. A vaginal obturator as claimed in claim 1, in which the strips are connected together by a binding.

3. An obturator as claimed in claim 1 in which the disc is composed of two plies of flexible sheet material cemented together, and the spring element is wholly sealed and enclosed between the plies.

OTTO POPPER.
